UNITED STATES PATENT OFFICE

170,604

MUSIC BOX CHRISTMAS ORNAMENT

John Petry, New York, N. Y., assignor to Raylite
Electric Corp., Bronx, N. Y., a corporation of
New York

Application October 4, 1952, Serial No. 21,701

Term of patent 7 years

(Cl. D56--1)

To all whom it may concern:

Be it known that I, John Petry, a citizen of the United States and resident of New York, in the county of Queens, State of New York, have invented a new, original, and ornamental Design for a Music Box Christmas Ornament, of which the following is a specification, reference being had to the accompanying drawing, forming a part thereof, and of which

Fig. 1 is a front elevational view of a music box Christmas ornament, showing my new design.

Fig. 2 is a top plan view thereof.

Fig. 3 is a side elevational view thereof, and
Fig. 4 is a rear elevational view thereof.

I claim:

The ornamental design for a music box Christmas ornament, as shown.

JOHN PETRY.
